INVENTOR.

Vincent Genoves,

BY

Geo. P. Kimmel. ATTORNEY.

UNITED STATES PATENT OFFICE.

VINCENT GENOVES, OF HONOLULU, TERRITORY OF HAWAII.

ILLUMINATED SCREW DRIVER.

Application filed May 25, 1926. Serial No. 111,610.

This invention relates to the class of tools and pertains particularly to a tool having an illuminating means associated therewith so that the working end of the tool may be 5 illuminated when it is necessary to work with the same in a position where there is insufficient light.

The primary object of this invention is the provision, in a manner as hereinafter set forth, of a tool having an illuminating element associated therewith and so carried that the light rays from said element will be projected directly upon the working end of the tool.

Another object of the invention is the provision, in a manner as hereinafter set forth, of a tool having an illuminating element associated therewith for illuminating the working end of the tool, and so built in the handle 20 of the tool as to be protected from injury, under all conditions.

The invention particularly contemplates the provision of an illuminating means for a tool such as a screw driver, or drill, having 25 a handle formed to receive an electric battery and having means at one end of said handle for making contact with the battery when desired. Upon the outer end of the handle there is positioned a sleeve having a 30 cone-shaped body projected from one end thereof and provided with apertures and the apex of the cone body is adapted to receive one end of a tool such as a screw driver shank. Within the end of the handle body, 35 over which the cone body is positioned, is an electric light element positioned eccentrically of the end of the body and bearing upon a plate through which a contact is made with the central electrode of the battery. This illuminating element is so positioned 40 beneath the cone-shaped body, that the rays projected from the element will fall directly upon the working end of the tool and is not placed in alignment with and 45 behind the end of the shank of the working member as in the case of other tools of this class.

A final object of the invention is the provision, in a manner as hereinafter set forth, 50 of an illuminated tool of the character above described, which will be strong and durable and able to stand the usual rough treatment which tools receive without injury to the illuminating means thereof, and further be light and comparatively inexpensive to manufacture.

The invention will be best understood from a consideration of the following detailed description taken in connection with the accompanying drawing forming a part of this 60 specification, with the understanding that the invention is not confined to any strict conformity with the showing of the drawing but may be changed and modified so long as such changes and modifications mark 65 no material departure from the salient features of the invention as expressed in the appended claims.

In the drawing:—

Figure 1 shows the tool embodying this 70 invention with the casing handle thereof in longitudinal section.

Figure 2 is a rear end view of the tool.

Figure 3 is a transverse section taken upon the line 3—3 of Figure 1. 75

Figure 4 is a transverse section taken upon the line 4—4 of Figure 1.

Figure 5 is a transverse section taken upon the line 5—5 of Figure 1 and, 80

Figure 6 is a transverse section taken upon the line 6—6 of Figure 1.

Referring now to the drawing in detail wherein like numerals of reference indicate corresponding parts throughout the several views, the numeral 1 indicates an elongated tubular casing which constitutes a combined tool handle and receptacle for an elongated cylindrical flashlight battery 2 of the usual well known type. As shown the casing 1 is of substantially greater length than the 85 battery 2 and fitted over one end of the casing is a rear end closure cap 3 having a recess 4 in the outer end thereof and further having extending through the longitudinal center thereof the contact screw 5 the head of which is positioned in the recess 4 below the outer edge thereof. Interposed between the end of the cap 3 and the end of the battery 2, is a spacing washer 6 of insulation material, having a central 90 aperture 7 formed therethrough for the passage of the contact screw 5. Under suitable conditions or when the tool is to be illuminated for use, the screw 5 is threaded inwardly until contact is made with the metallic end of the battery 2 to complete a circuit in a manner hereinafter to be set forth. As is well known batteries of the type here shown are surrounded by a relatively thick wrapper of cardboard 8, which wrapper protects the battery from contact with the metallic wall of the receptacle 1. The central 95

- electrode 9 of the battery extends from the longitudinal center of the other end thereof in the usual manner, as shown in Figure 1.
- Overlying the forward end of the battery 2 is an annular copper contact plate 10 having a central aperture for the passage of an electrode 9 of the battery which electrode contacts with the wall of the aperture to make contact with the plate. Positioned against the inner wall of the handle casing 1 at the forward end of the battery 2, is a thin annular member 11 which is secured by the pins 12 to the wall of the casing 1 as shown in Figure 4. This ring 11 holds the battery 2 from moving forwardly in the casing in the manner shown in Figure 1 and the forward edge of the ring is provided with a notch 13 for the following set forth purpose.
- Adapted to be positioned within the forward end of the handle casing 1 is an annular plate member 14 having soldered or otherwise secured to the underface thereof the tongue 15, one end of which overlies the edge of the plate and is adapted to be positioned in the notch 13 in the ring 11 to hold the plate 14 against revolution when the same is seated upon the end of the ring 11. This plate 14 as is clearly shown in Figures 1 and 5 closes the forward end of the casing 1 forwardly of the battery 2.
- Formed through the plate or disc 14 adjacent the periphery thereof is an aperture 16 having a sleeve extending outwardly from the edge thereof as indicated at 16, and this sleeve is threaded to receive the base 17 of an incandescent lamp 18.
- As is shown in Figure 1, when the disc 14 is in position and carrying the incandescent bulb 18 in the socket 16, the base portion 17 of the bulb contacts with the plate 10 and is thereby electrically connected with the central electrode 9 of the battery.
- As shown the disc 14 is positioned inwardly of the forward end of the handle casing 1 and when thus placed in position there is positioned upon the top of the disc with in the end of the casing the retaining resilient split ring member 19. The forward end edge of the casing 1 is provided with a notch at the point 20 for the purpose hereinafter described.
- Adapted to be positioned over the forward end edge of the casing 1 is a sleeve 21 carrying a pin 22 which engages in the notch 20 of the casing to insure the sleeve being placed thereon in the proper position. Extending from one end of the sleeve 21 is a cone-shaped body 23 having formed in the wall thereof diametrically oppositely positioned apertures 24 and further having extending from the apex thereof a centrally apertured neck 25 adapted to receive one end of the shank 26 of a screw driver member 27, or any other tool. The retaining positioning pin 22 carried by the sleeve 21 when in engagement with the notch 20 of the casing 1, so positions the sleeve that one of the apertures 24 of the cone-shaped body 23 directly overlies the incandescent lamp 18 so that it will be readily seen that when the lamp is lighted the rays of light therefrom will pass directly through the aperture 24 and fall upon the working end 27 of the tool. It is to be noted that due to the eccentric positioning of the incandescent member 18 all of the light therefrom will fall directly upon the work and the working end of the tool.
- From the foregoing description it will be readily seen that, upon screwing the contact member 5 inwardly to bring the same in contact with the end of the battery 2, a circuit will be set up through the screw member 5, the end cap 3 and the casing 1 to and through the disc 14 to the lamp base 17 and from there back through the copper contact disc 10 to the central electrode 9 of the battery completing the circuit. As has been before stated the usual carboard wrapper 8 which surrounds batteries of this type prevents accidental contact of the metal wall of the battery with the casing, the only contact that can be made with the wall of the casing must be made by means of the contact screw 5 in the end of the tool.
- Having thus described my invention what I claim is:—
1. A tool of the character described, comprising a handle, a working member, a sleeve at one end of said member for engagement over one end of said handle and having a cone portion extending therefrom provided with an eccentrically located aperture and adapted to receive said member end, illuminating means within said cone portion eccentrically of the end of said handle and in alignment with said aperture, for directly illuminating the other end of said member, a battery in said handle and having a center electrode, and a contact element concentrically of and engaged by the illuminating means and the center electrode.
2. A tool of the character described, comprising a handle casing adapted to receive an electric battery having a central electrode, means forming a continuation of said center electrode, means for maintaining an incandescent bulb eccentrically in one end of said casing in contact with said means, a structure having an eccentrically located aperture enclosing the forward end of said casing and covering said incandescent bulb, incandescent bulb and said aperture being in alignment, means for holding a working element in said apertured structure in longitudinal alignment with said casing to receive light rays upon the working end thereof from said bulb through said aperture in said structure, and

means for completing circuit of the bulb to illuminate the latter.

3. In an illuminated tool of the character described, a handle casing adapted to receive an electric battery, such battery having a central electrode projecting from one end thereof, a contact plate overlying one end of said battery and surrounding said central electrode, a notched means in said casing 10 for holding said battery in position, a disc member positioned transversely of said casing adjacent said central electrode and bearing upon and held in position by said notched member through engagement with the notch 15 thereof, an incandescent element carried by

and extending through said disc adjacent the periphery thereof and contacting with said contact plate a working element carrying apertured body engaging over the end of said casing and covering said incandescent element in such manner as to expose the same through one of the apertures therein to enable light rays therefrom to fall directly upon the working end of the working element, and means for closing a circuit between said battery and incandescent element 20 to illuminate the element. 25

In testimony whereof, I affix my signature hereto.

VINCENT GENOVES.
